UNITED STATES PATENT OFFICE

RAYMOND L. PLUMLEY, OF BROOKLYN, NEW YORK, ASSIGNOR TO FREDERICK OSANN COMPANY, OF NEW YORK, N. Y., A CORPORATION OF NEW YORK

OVERSEAMING SEWING MACHINE

Application filed May 19, 1927. Serial No. 192,698.

My present invention relates to sewing machines for overseaming and particularly to the type of overseaming machines especially adapted for use in fur stitching which is disclosed in my prior Patent No. 897,486, granted September 1, 1908. While the machine of my said prior patent has been very extensively and successfully used, its operation has been attended with certain disadvantages which it is the purpose of the present invention to overcome. An important object of the present invention is to provide a sewing machine of the type disclosed in my prior patent with improvements adapted to facilitate its operation at higher speeds than are practically attainable with the machine disclosed in my prior patent.

One improvement in this machine over that of my prior patent, forming a part of the present invention and contributing materially to the higher speed capacity of the improved machine, pertains to the means for supporting the looper and giving the latter its movements in a plane parallel to the line of movement of the needle. The means herein disclosed for the purpose last referred to are characterized by the easy motion of the various movable parts, by the avoidance of lost motion, and by the range and ease of adjustment of the looper path.

In the operation of a high speed sewing machine, proper lubrication is a matter of much practical importance, and my present invention comprises an improved oiling system especially adapted for use in an overseaming machine of the general type disclosed in my prior patent. The present invention also comprises improvements in the work feeding means.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described a preferred embodiment of the invention.

Of the drawings:

Fig. 1 is a plan view with a portion of the casing removed;

Fig. 2 is an elevation in section on the line 2—2 of Fig. 1;

Fig. 3 is a partial section on the line 3—3 of Fig. 1 and showing a portion only of the apparatus shown in Fig. 2;

Fig. 4 is an elevation of a portion of the machine taken at right angles to Fig. 3 and with parts broken away and in section;

Fig. 5 is an elevation taken similarly to Fig. 2 but on a larger scale and partly broken away, and showing a portion only of the apparatus shown in Fig. 2;

Fig. 6 is a partial plan in section on the line 6—6 of Fig. 2;

Fig. 7 is a partial section on the line 7—7 of Fig. 1;

Fig. 8 is a partial sectional plan taken on the line 8—8 of Fig. 2;

Fig. 9 is a section on the broken line 9—9 of Fig. 5; and

Fig. 10 is a sectional view of one of the connecting rods.

The frame-work or housing of the machine shown in the drawings comprises a main box-like portion A, a removable front portion A', and a removable top cap portion A''. The housing is provided with upper and lower bearings A⁴ and A⁵ for the power actuated shaft B which carries at its upper end the feed disc C. The shaft B has a gear B² adjustably secured to it as by means of set screws B'. The gear B² rests upon the upper end of the bearing A⁵. A collar B³ adjustably secured, as by a set screw B⁴, to the shaft B, engages the underside of the bearing A⁴. By suitable adjustments of the parts B² and B³ on the shaft B, the proper elevation of the feed disc C may be secured and maintained.

The gear B² is driven by a cooperating crown gear D, which is secured to the shaft D' journaled at its ends on the trunnion pivots D². The latter are threaded in the housing wall A and are adjustable to move the shaft D' in the direction of its length and thereby take up lost motion between the

gears B² and D. Lock nuts D³ secure the pivots D² in any desired position.

The gears B² and D are so constructed and arranged that when gear D is rotated in the counter-clockwise direction as seen in Figs. 2 and 5, it rotates the gear B² so that the feed disc C is rotated in the counter-clockwise direction as shown in Fig. 1; but the gear B² is incapable of rotating the gear D. In consequence, the gear D forms a lock which holds the gear B² against movement other than its regular feeding movements brought about by the rotation of the gear D. It is unnecessary to describe the character of the teeth on the gears B² and D employed to insure the above described operation as that forms no part of my present invention, and in this respect the gears B² and D may be identical with the similarly designated gears of my prior Patent No. 897,486.

The gear D is given intermittent rotative movements in the counter-clockwise direction by an oscillating actuating lever E and clutch provisions, now to be described, by means of which the lever E is locked to the gear D when the lever E is turned in the counter-clockwise direction, and is released from the gear D when turned in the opposite direction. The lever E is formed with an aperture E' through which the shaft D' passes. The aperture E' is elongated in a direction transverse to the length of the lever E to permit some corresponding transverse play of the lever relative to the shaft D'. Associated with the lever E are two clutch parts ea' and ea² arranged one below and the other above the lever. Each of the two clutch parts is formed at its opposite ends with spaced apart cylindrical bearing surfaces e³ which fit against the inner wall of a cylindrical flange D⁴ formed at the front side of the gear D, as viewed in Figs. 2 and 5. The lever E is formed with cam-like projections E² and E³ at its lower and upper sides respectively, which engage bearing surfaces formed on the members ea' and ea² respectively. In the construction shown these bearing surfaces are the parallel upper and lower sides of the members ea' and ea² respectively. The cam portions E² and E³ are diametrically opposed to one another, the cam E² being to the left and the cam E³ to the right of a plane including the axis of the gear D and transverse to the length of the members ea' and ea². A compression spring e⁵ acts between the lever E and the right end of the member ea' as seen in Fig. 5, and a similar compression spring e⁶ acts between the other end of the member ea² and the lever E. A spring e⁴ acts between the left hand end of the part ea', as seen in Fig. 5, and a lug or finger e' carried by the lever E, in a direction tending to turn the member ea' about the axis of the gear D in the clockwise direction when the lever E is turned in the clockwise direction, and a similar spring e⁴ acts similarly

between the right hand end of the member ea' and a lug or shoulder e² carried by the lever E. As shown, the lugs e' and e² are integral portions of a part e rigidly secured to the member E.

When force is applied to the outer end of the lever member E to turn the latter in the counter-clockwise direction, the cam portions E² and E³ tend to spread the members ea' and ea² apart and this creates a frictional engagement between the surfaces e³ of the members ea' and ea² and the inner wall of the flange D⁴ which prevents movement of the members ea' and ea² relative to the gear D. The lever member E is thus locked to the gear D so that the latter shares the counter-clockwise turning movement of the lever E. The springs e⁵ contribute to the operation just described by normally holding the corresponding ends of the members ea' and ea² snugly in contact with the flange D⁴ so that there is practically no lost motion to be overcome when the initial spreading apart of the members ea' and ea² occurs. When the movement of the lever E is reversed, the cam portions E² and E³ cease to press the members ea' and ea² apart and the springs e⁴ and e⁵ acting on the ends of the members ea' and ea² then cause the latter to turn about the axis of the member D with the lever E. As shown, the lever E is formed with a slot or groove E⁶ in its rear side loosely receiving the flange D⁴, but there is no operative engagement of the walls of the slot with the flange.

As a safeguard against any tendency of the gear D to rotate in the clockwise direction, as a result of lost motion or otherwise, I advantageously provide a suitable locking device or brake. This, as shown, is in the form of a bar eb formed with a slot or groove e¹⁰ in one side which receives the flange D⁴. The outer end of the bar eb bears against a stop A¹¹ carried by the machine housing and a spring e¹¹ tends to hold the brake in the position shown in Figs. 2 and 5 in which the walls of the slot or groove e¹⁰ engage the inner and outer walls of the flange D⁴ so as to positively hold the gear D against rotation in the clockwise direction. The spring e¹¹ yields to permit the slight turning movement of the bar eb necessary to permit the flange D⁴ to move freely in the slot or groove e¹⁰, when the gear D is rotating in the counter-clockwise direction.

The outer end of the member E is connected by a pivot pin E⁷ to a lever F. The lever F is pivotally connected to the housing A through a fulcrum part F' passing through a longitudinal slot F² in the lever F, and having a threaded extension which passes through a horizontal slot A⁸ in the housing A and may be clamped in any desired position in said slot by a nut F⁹. The end of the lever F opposite to that connected to the member E is pivotally connected by a pivot pin G' to

a link G, the upper end of which forms an eccentric strap portion G¹² surrounding an eccentric disc H' secured to the main driving shaft H of the sewing machine, which is 5 journaled in bearings formed in the housing A.

The outer feed disc C' is journaled on a shaft C², the lower end of which is held in a pinch socket formed in the outer end of the 10 bent arm or goose neck I and controlled by the pinch screw I¹⁴ by which a vertical adjustment may be had of the shaft C² and the disc C' thereby adjusted with respect to the disc C in the direction of their axes. Above 15 the feed disc C' is a member I² connected by a screw I³ to the shaft C². The member I² is provided with a groove I⁴ in which the needle J' travels and is protected. The 20 goose-neck I is secured to parallel rods I⁵ and I⁶ which slide in bearings formed in the housing wall A to move the disc C' toward and away from the disc C.

The lower bar I⁶ is notched or recessed at 25 I⁷ to receive the upper end of an arm I⁸ secured to a rock shaft I⁹ so that the rotation of the latter will move the goose-neck I and thereby move the feed disc C' away from or return it towards the feed disc C. The feed 30 disc C' is normally urged toward the feed disc C with the desired work holding force by means of a tension spring I¹¹ connected at one end to the end of a second arm I¹⁰ of the rock shaft I⁹ and adjustably secured at its 35 other end to the machine housing by a bolt I¹². The rock shaft I⁹ is turned to move the feed disc C' away from the feed disc C by a third arm I¹³ secured to the rock shaft I⁹ and projecting through a slot A¹² formed in the rear wall of the machine housing. It will 40 be observed that the free end of the arm I¹³ moves upward to separate the feed discs C and C'. This facilitates the operation by a treadle in the form of a lever of the first class to the rear end of which the arm I¹³ is 45 connected. This arrangement permits the operator to separate the feed discs by depressing the heel end of the treadle as is practically desirable, because it is the mode of treadle operation which the operators of such 50 machines generally prefer and to which they are ordinarily accustomed, making it unnecessary to employ a rocker lever intermediate the treadle and the arm I¹³ as is the case with the machine shown in my patent, 55 897,486, granted September 1, 1908.

The needle bar J carrying the needle J' at its front end is slidingly mounted in bearings in the front and rear walls of the housing A. The bar J is given its longitudinal reciprocations by means of an arm U' pivotally supported by a shaft U and connected to the needle bar by a link U² pivotally connected at one end to the end of the arm U', and at its other end to an arm J² adjustably clamped 60 on the needle bar. The arm U' is oscillated

by a connecting rod W pivotally connected at one end through a pin U³ to the arm U' at a point intermediate the end of the latter and the shaft U. The other end of the connecting rod W is provided with a split eccentric 70 strap portion W' surrounding an eccentric disc W³ on the main shaft H.

The bent looper M is adjustably secured to a looper bar M' by the chuck M² carried by the bar M'. The looper bar M' is rotatively 75 mounted in the movable looper supporting frame or member M³. In the preferred construction illustrated in the drawings, the member M³ is given its movements by a crank shaft M⁵ journaled in a bearing m and provided at one end with a crank arm M⁴ carrying a crank pin M⁶ which passes through a bearing formed on the member M³ adjacent the front end of the latter. At its opposite end the crank shaft M⁵ has a crank arm M⁷ 80 carrying a crank pin M⁸ to which is connected one end of a connecting rod M⁹. At its opposite end the connecting rod M⁹ is provided with a split eccentric strap portion M¹⁰ fitting about an eccentric crank disc M¹¹ 85 carried by the main shaft H of the machine. At its rear end the member M³ is formed with a bearing for a crank pin M¹² carried by a crank arm M¹³ having a crank shaft body portion M¹⁴ journaled in the machine housing, or 90 rather, as shown, in a bracket A¹¹ adjustably secured to the housing member A.

The looper bar M' is oscillated about its axis as in my prior Patent No. 897,486, by means of an arm comprising a yoke or hub portion M¹⁶ detachably clamped on the bar M', and an extension M¹⁷ carrying a cam roll M¹⁸ received in a cam slot M¹⁹ formed in the side of a cam disc M²⁰ carried by the main shaft H. The cam disc M²⁰ is advantageously 100 provided as shown, with a suitably disposed counter-balance M⁵¹ and is of sufficient mass to serve as a fly-wheel for balancing or steady- 105 ing the operation of the machine.

The bearing m is mounted on a bracket portion A¹² of the housing body shaped to provide a seat at its upper side for the bearing member m. As shown this seat is formed with a groove A³ to receive a rib on the under- 110 side of the bearing m guiding the latter in any adjustment on its seat in a direction transverse to the shaft M⁵ which it may be desirable to give the bearing. The bearing m, as shown, is formed with a passageway for the shaft M⁵, and with a horizontal kerf M³⁰ 115 which extends across said passageway from one side of the bearing so that the bearing may be tightened up from time to time to compensate for wear, by drawing the walls at the opposite sides of the kerf toward one another by tightening up the screws M²⁰. The bearing m is secured on its seat by screws M²¹ 120 passing through holes in the bearing which are enlarged to permit the adjustment of the bearing m in the groove A³. A further pos- 125 130

sible adjustment of the looper frame movement and position is obtainable by interposing a shim or shims M^4 of varying thickness between the bearing m and its seat on the bracket A^{12} and thereby varying the elevation of the shaft M^5 . Another adjustment of the looper frame may be secured, with the type of construction illustrated, by forming the bracket A^{11} with vertically elongated holes for the screws or bolts M^{15} by which the bracket A^{11} is secured to the housing member A. Another looper frame adjustment which may be had with the construction illustrated is obtained by adjusting the crank arms M^4 and M^7 angularly with respect to one another about the axis of the shaft M^5 by which they are rigidly connected in normal operation.

By means of one or more of the described looper frame adjustments and by the adjustment of the looper M in the chuck M^2 connecting it to the looper bar M' it is possible to effect practically any desired adjustment of the movements of the looper frame M^3 and thereby to vary the elevation of the looper at either end of its stroke, and to change the timing of the rising and falling movements of the looper relative to the stroke of the needle as may be required in adjusting the machine for the best operating conditions with different kinds or styles of work and different styles and sizes of needles. Of the described adjustments of the looper frame M^3 , the angular adjustment of the crank arms M^4 and M^7 and the vertical adjustment of the bracket A^{11} are the most important, and are of themselves ordinarily sufficient since they permit of a substantial differential adjustment in a vertical plane of the looper positions at the two ends of its backward and forward movement.

A desirable characteristic of the means shown for giving the looper frame its movements arises from the fact, that, the movements of the crank pin M^8 are along an arc, to which the line of action of the connecting rod M^9 is preferably a tangent when the pin M^8 is approximately at the center of said arc. In consequence, at no point along said arc does the tangent at that point make more than a relatively small angle with the plane including the axis of the shaft H and the axis of the crank pin M^8 . The latter therefore, does not approach at all closely to a dead center position and its oscillatory movement is of a character well adapted for high speed operation.

In a machine of the type described, particularly when operated at the relatively high speeds for which the machine is especially designed, the matter of proper lubrication of the various bearing surfaces is of much practical importance. In accordance with the present invention proper lubrication is effected by providing an oil reservoir X with a multiplicity of outlets X' each discharging oil to a

corresponding pipe Y leading to an oil receiving space formed in or associated with the particular bearing or bearings receiving oil through said pipe. As shown, the oil reservoir X is in the form of a shallow receptacle formed in the cover part A² and provided with a hinged cover X². Each reservoir oil outlet X', as shown, is in the form of a hole of proper size formed in the bottom wall of the reservoir X. Each hole X', as shown, is counter-bored or enlarged at its upper end, and receives in said enlargement a wad or mass Z of felt or the like, by which the oil is filtered, and which serves also to retard the flow of oil through the outlet to the pipe Y connected to the lower end of the hole. By suitably proportioning the sizes of the enlarged retarding material containing portions of the outlet openings X', a gravity oil discharge at the proper rate to each of the different bearings may be obtained even though one of such bearings may require but a single drop of oil during a period in which another bearing requires twenty or more drops of oil. In general, there is a separate reservoir orifice X' and pipe Y for each bearing to be lubricated, and associated with each bearing is a corresponding oil receiving space YA into which the corresponding pipe Y discharges. The spaces YA preferably contain felt or the like which slowly passes the oil received. Such of the spaces YA as are formed in eccentric straps or other reciprocating parts are suitably elongated. As shown, all the oil employed for lubricating the bearings for the shaft B and for lubricating the gear teeth on the gear B² is supplied through a single pipe Y which delivers oil to the upper end of a bent pipe YB secured to the housing framework and having its lower end discharging into a depression A¹⁵ formed in the upper face of the part in which the bearing A⁴ is formed at the margin of that bearing. As shown, the shaft B is formed with a groove B¹⁵ in its outer surface leading from the depression A¹⁵ down through the bearing A⁴. In consequence, some of the oil received in the depression A¹⁵ passes down through the groove B¹⁵ and films over the top of the gear B². Some of this oil reaches the periphery of the gear and flows down over the teeth of the gear thereby lubricating the others. Another portion of the oil reaching the top surface of the gear B² passes through an opening B¹⁶ formed in the gear, to the bearing surface at the top of the part in which the bearing A⁴ is formed.

Another pipe YC secured to the housing member A and receiving oil at its upper end from a corresponding pipe Y delivers oil at its lower end into a groove U⁴ formed in the upper side of the link U² by which the lever U¹ is connected to the needle bar J, the oil thus supplied lubricating the pivotal connections at the two ends of the link U². The bearing for the lower end of the lever U¹ is

- lubricated by means of oil supplied to the receptacle or space YA formed in the eccentric strap portion W' of the connecting rod W and a channel formed in the latter 5 through which the oil passes from the eccentric bearing surface down to a transverse oil pipe W¹¹ discharging into an oil space U¹⁰ formed in the hub at the lower end of the lever U'.
- 10 The cooperating bearing surfaces of the crank pin M⁸ and connecting rod M⁹ are lubricated by oil supplied through a channel M⁵⁰ in the rod M⁹ from the bearing surface of the portion of the rod surrounding the 15 crank disc M¹¹. To secure the desired oil flow through the channel M⁵⁰ which is necessarily inclined upwardly from the crank disc M¹¹ to the crank pin M⁸, located at a higher level, the channel, or at least the portion 20 thereof adjacent the bearing for the disc M¹¹, is inclined in a certain direction to the plane connecting the axes of the disc M¹¹ and pin M⁸ as shown in Fig. 10. The direction of the inclination is determined by the direction 25 of rotation of the disc M¹¹, and is such that the centrifugal force action on the oil carried around the axis of the disc M¹¹ by the rotation of the latter tends to drive the oil into the corresponding end of the channel M⁵⁰.
- 30 In other words, the inclination of the channel M⁵⁰ is such that its end in the bearing for the disc M¹¹ faces toward and not away from the direction from which any point on the periphery of the disc M¹¹ approaches it.
- 35 The rate at which oil is passed through the channel M⁵⁰ is increased by the pocket M⁵² into which the channel opens formed in the convex bearing wall at the side of the channel from which the oil approaches. The 40 novel lubricating provisions disclosed but not claimed herein are claimed in my application Serial No. 382,860, filed August 2nd, 1929, as a division of this case, and the novel clutch mechanism for imparting its movements to 45 the gear D disclosed but not claimed herein, is claimed in my application Serial No. 382,861, also filed August 2nd, 1929, as a division of this case.
- While in accordance with the provisions 50 of the statutes, I have illustrated and described the best form of embodiment of my invention now known to me, it will be apparent to those skilled in the art that changes may be made in the form of the apparatus 55 disclosed without departing from the spirit of my invention as set forth in the appended claims and that in some cases certain features of my invention may be used to advantage without a corresponding use of other 60 features.
- Having now described my invention, what I claim as new and desire to secure by Letters Patent is:—
1. In a sewing machine for overseaming comprising a supporting structure, a reciprocating needle and a driving shaft having a crank portion both mounted in said structure, a cooperating looper and a looper supporting member, the improved means for supporting and moving said member comprising a rock-shaft extending transversely to the direction of needle movement, a bearing for said rock-shaft adjustable to move said rock-shaft transversely to its length, a crank carried by said rock-shaft and operatively connected to said member, a second crank carried by said rock-shaft, an operative connection between said second crank and said crank portion, and guiding means engaging said member at a distance from the connection between said member and the first mentioned crank. 75
  2. In a sewing machine for overseaming comprising a supporting structure, a reciprocating needle and a driving shaft having a crank portion both mounted in said structure, a cooperating looper and a looper supporting member, the improved means for supporting and moving said member comprising a rock-shaft extending transversely to the direction of needle movement, a bearing for said rock-shaft adjustable to move said rock-shaft transversely to its length in vertical and horizontal directions, a crank carried by said rock-shaft and operatively connected to said member, a second crank carried by said rock-shaft, an operative connection between said second crank and said crank portion, and guiding means engaging said member at a distance from the connection between said member and the first mentioned crank. 80
  3. In a sewing machine for overseaming comprising a supporting structure, a reciprocating needle and a driving shaft having a crank portion both mounted in said structure, a cooperating looper, and a looper supporting member, the improved means for supporting and moving said member comprising a rock-shaft journaled in said structure and extending transversely to the direction of needle movement, a crank carried by said rock-shaft and operatively connected to said member, a second crank carried by said rock-shaft, an operative connection between said second crank and said crank portion, a guiding connection carried by said structure and engaging said member at a distance from the connection between said member and the first mentioned crank, and means for adjusting said guiding connection relative to said structure in a direction parallel to the plane of movement given said member by said rock-shaft and transverse to the general direction of said movement. 105
  4. In a sewing machine for overseaming comprising a supporting structure, a reciprocating needle and a driving shaft having a crank portion both mounted in said structure, a cooperating looper, and a looper sup- 110

- porting member, the improved means for supporting and moving said member comprising a rock-shaft journaled in said structure and extending transversely to the direction of needle movement, a crank carried by said rock-shaft and operatively connected to said member, a second crank carried by said rock-shaft, an operative connection between said second crank and said crank portion, said 5 cranks being angularly adjustable relative to one another about the axis of said rock-shaft, a guiding connection carried by said structure and engaging said member at a distance from the connection between said member 10 and the first mentioned crank, and means for adjusting said guiding connection relative to said structure in a direction parallel to the plane of movement given said member by said rock-shaft and transverse to the general direction of said movement. 15
5. In a sewing machine for overseaming, comprising a supporting structure, a reciprocating needle and a driving shaft having a crank portion both mounted in said structure, a cooperating looper, and a looper supporting frame, the improved means for supporting and moving said frame comprising a rock-shaft journaled in said structure and extending transversely to the direction of needle movement, a crank carried by said rock-shaft and operatively connected to said frame, a second crank carried by said rock-shaft, an operative connection between said second crank and said driving shaft crank 25 portion, each of said cranks having an angularly adjustable connection with said rock-shaft, and a supporting link having its upper end pivotally mounted in said structure and its lower end pivotally connected to said 30 frame and engaging the latter at a distance from the point of connection of said frame to said first mentioned crank, whereby said frame is bodily tiltable relative to said structure. 35
- 40 6. In a sewing machine for overseaming, the combination with a supporting structure, a looper, a looper arm connected thereto, a looper frame carrying said looper and looper arm, and a drive shaft, of mechanism for supporting and bodily moving said looper frame relative to said structure including a rock-shaft journaled in said structure and extending transversely of said looper frame, a crank carried by said rock-shaft and journaled in said looper frame, a second crank carried by said rock-shaft and having a crank pin movable in an arc having its convex side uppermost, a connecting rod operatively connecting said pin to said drive shaft 45 and arranged with its line of action substantially tangential to said arc when said pin is in the middle of said arc, a supporting link carried by said structure and pivotally connected to said looper frame at a 50 distance from the point of connection of said 55 60 65 70 75 80 85 90 95 100 105 110 115 120 125 130
- looper frame to said first mentioned crank, and each of said looper frame connections being adjustable relative to said structure to vary the position of the looper frame in the plane in which it is movable. 76
- Signed at New York in the county of New York and State of New York, this 16th day of May, A. D. 1927.
- RAYMOND L. PLUMLEY.
